Primary Examiner — Mitchell I. Siegel

(57)

CLAIM

The ornamental design for a golf club head, as shown and described.

DESCRIPTION

FIG. 1 is a front perspective view of a golf club head; FIG. 2 is a back perspective view of the golf club head of FIG. 1;

FIG. 3 is a front elevational view of the golf club head of FIG. 1;

FIG. 4 is a rear elevational view of the golf club head of FIG. 1;

FIG. 5 is a top view of the golf club head of FIG. 1;

FIG. 6 is a bottom view of the golf club head of FIG. 1;

FIG. 7 is a left side view of the golf club head of FIG. 1;

FIG. 8 is a right side view of the golf club head of FIG. 1;

FIG. 9 is a front perspective view of a second embodiment of a golf club head;

FIG. 10 is a back perspective view of the golf club head of FIG. 9;

FIG. 11 is a front elevational view of the golf club head of FIG. 9;

FIG. 12 is a rear elevational view of the golf club head of FIG. 9;

FIG. 13 is a top view of the golf club head of FIG. 9;

FIG. 14 is a bottom view of the golf club head of FIG. 9;

FIG. 15 is a left side view of the golf club head of FIG. 9;

FIG. 16 is a right side view of the golf club head of FIG. 9;

FIG. 17 is a top perspective view of a third embodiment of a golf club head;

FIG. 18 is a bottom perspective view of the golf club head of FIG. 17;

FIG. 19 is a front elevational view of the golf club head of FIG. 17;

FIG. 20 is a rear elevational view of the golf club head of FIG. 17;

FIG. 21 is a top view of the golf club head of FIG. 17;

FIG. 22 is a bottom view of the golf club head of FIG. 17;

FIG. 23 is a left side view of the golf club head of FIG. 17;

FIG. 24 is a right side view of the golf club head of FIG. 17;

FIG. 25 is a top perspective view of a fourth embodiment of a golf club head;

FIG. 26 is a bottom perspective view of the golf club head of FIG. 25;

FIG. 27 is a front elevational view of the golf club head of FIG. 25;

FIG. 28 is a rear elevational view of the golf club head of FIG. 25;

FIG. 29 is a top view of the golf club head of FIG. 25;

FIG. 30 is a bottom view of the golf club head of FIG. 25;

FIG. 31 is a left side view of the golf club head of FIG. 25;

FIG. 32 is a right side view of the golf club head of FIG. 25;

FIG. 33 is a top perspective view of a fifth embodiment of a golf club head;

FIG. 34 is a bottom perspective view of the golf club head of FIG. 33;

FIG. 35 is a front elevational view of the golf club head of FIG. 33;
